ARCH TYPE ELECTRICAL ROAD SWITCH

Oldric J. La Bell, Washington, D. C.; dedicated to
the free use of the People of the United States
of America

Application May 2, 1938, Serial No. 205,441

2 Claims. (Cl. 200—86)

(Granted under the act of March 3, 1883, as
amended April 30, 1928; 370 O. G. 757)

This application is made under the act of
March 3, 1883, as amended by the act of April 30,
1928, and the invention herein described, if pat-
5 ented, may be manufactured and used by or for
the Government of the United States of America
for governmental purposes without the payment
to me of any royalty thereon.

I hereby dedicate the invention herein de-
scribed to the free use of the People of the United
10 States of America to take effect on the granting
of a patent to me.

The invention relates to road switches and is
more particularly concerned with a road switch
15 of the arch type which is actuated by vehicles
passing thereover.

One of the objects of this invention is the pro-
vision of a switch of the type mentioned which
is so constructed that replacements of parts ordi-
narily worn more quickly can be made without
20 the necessity of replacing other parts.

Another object of this invention is the provision
of a switch of the type mentioned in which the
contact is broken by the action of a resilient arch
alone rather than by combination of arch effect
25 with other means, or solely by means other than
the arch effect.

A further object of this invention is the pro-
vision of such a switch that is waterproof thus
obviating short circuits due to moisture, rain, etc.
30 The following description, considered together
with the accompanying drawing, will disclose
this invention more fully, its construction and
operation of parts, and further objects and ad-
vantages thereof will be apparent.

35 In the drawing:

Figure 1 is an elevational cross-section view
showing a fragmentary portion of an illustrative
form of this invention longitudinally.

Figure 2 is an end cross-sectional view of the
40 form shown in Figure 1 at a point indicated by
the line 2—2.

Referring with more particularity to the draw-
ings in which like numerals designate like parts,
an outer flanged casing 1, of rubber or other
45 resilient electrical non-conductor material, pref-
erably tough and impervious, is adapted to be dis-
posed transversely across a highway surface, and
has a hollow arch section into which is remov-
ably fitted, telescopically, an inner arch casing 2,
50 also hollow. A metal electrical conductor 3, such
as spring steel, is secured on the base of the in-

terior of the inner arch 2. Another electrical
conductor 4 is carried on the top of said inner
arch 2, and is held in place by lacing it through
holes punched along the crown of the arch at
intervals of any convenient distance, such as one 5
inch.

Each conductor may then be attached to a lead
cable and inserted into any electrical circuit.
The ends of the outer casing 1 are then vulcanized
to make it water tight. 10

When this device is disposed across a highway,
15 vehicles passing over it deflect the resilient arch
thereby bringing into contact the two conductor
strips 3 and 4, which contact completes an elec-
trical circuit. The circuit may be used for oper-
ating various instruments such as traffic counters,
chronographs, bells, traffic lights, etc. When the
20 vehicles clear the device the arch returns to its
original position, carrying with it the upper con-
ductor strip 3, thus breaking the contact. Should 25
the outer casing become worn or punctured, it
may be replaced with a new casing, while the in-
ner casing 2, and its conductors, are utilizable
again in the new casing.

Any convenient means may be used to attach 25
the device to the highway surface, such as steel
pins inserted through grommets at intervals in
the flange of the outer casing 1, or the ends of the
device may be attached to steel pins driven into
earth shoulders of a highway. For temporary 30
placement, rubber cement may be used.

Having thus described my invention, what I
claim is:

1. An electrical road switch comprising a lon-
gitudinal, hollow, resilient outer casing; a longi-
tudinal, hollow, resilient inner casing removably
fitted within said outer casing; an electrical con-
ductor secured on the base of the interior of said
inner casing; and another electrical conductor
longitudinally woven in the crown of said inner 40
casing. 35

2. An electrical road switch comprising a longi-
tudinal, hollow, resilient outer casing hermeti-
cally sealed; a longitudinal, hollow, resilient in-
ner casing removably fitted within said outer 45
casing; an electrical conductor secured on the
base of the interior of said inner casing; and
another electrical conductor longitudinally woven
in the crown of said inner casing. 50

OLDRIC J. LA BELL.
